Primary Examiner — Jennifer Rivard*Assistant Examiner* — April Rivas*(74) Attorney, Agent, or Firm* — Dan DeLaRosa**CLAIM**

The ornamental design for a tool case, as shown and described.

DESCRIPTION

FIG. 1 is a front perspective view of the tool case of the present invention showing my new design;

FIG. 2 is a front side elevational view thereof;

FIG. 3 is a back side elevational view thereof;

FIG. 4 is a side elevational view thereof;

FIG. 5 is another side elevational view thereof;

FIG. 6 is a top plan view thereof; and,

FIG. 7 is a bottom plan view thereof.

The broken lines immediately adjacent to the circular features in FIGS. 1 and 2 represent the bounds of the claim. The remaining broken lines illustrate portions of the tool case. None of the broken lines forms any part of the claimed design.
